United States Patent Office

Des. 224,272
Patented July 11, 1972

224,272

PHOTOGRAPHIC CAMERA OR SIMILAR ARTICLE

James M. Conner, Mamaroneck, N.Y., and Richard H. Davison, Sudbury, Milton S. Dietz, Lexington, and Bruce K. Johnson, Andover, Mass., assignors to Polaroid Corporation, Cambridge, Mass.

Continuation-in-part of design application Ser. No. 23,741, June 23, 1970. This application Apr. 15, 1971, Ser. No. 134,522

Term of patent 14 years

Int. Cl. D16—01

U.S. Cl. D61—1

FIG. 2

FIG. 3

FIG. 4

FIG. 5

FIG. 6

FIG. 7

FIG. 1 is a perspective view of a photographic camera or similar article showing our new design;

FIG. 2 is a right side elevational view thereof;

FIG. 3 is a front elevational view thereof;

FIG. 4 is a left side elevational view thereof;

FIG. 5 is a top plan view thereof;

FIG. 6 is a rear elevational view thereof; and

FIG. 7 is a bottom plan view thereof.

This is a continuation-in-part of design application, Ser. No. 23,741, filed June 29, 1970.

We claim:

The ornamental design for a photographic camera or similar article, as shown.
